UNITED STATES PATENT OFFICE.

JOHN F. A. HOORT, OF NEW YORK, N. Y., ASSIGNOR TO THE EAST ROCKFORD MANTEL COMPANY, OF ROCKFORD, ILLINOIS.

DESIGN FOR A MANTEL.

SPECIFICATION forming part of Design No. 24,281, dated May 7, 1895.

Application filed April 4, 1895. Serial No. 544,497. Term of patent 3½ years.

To all whom it may concern:

Be it known that I, JOHN F. A. HOORT, a citizen of the United States, residing at New York, in the county of New York and State of New York, have invented and produced a new and original Design for Mantels; and I do hereby declare the following to be a full, clear, and exact description of the same, reference being had to the accompanying drawing, forming a part thereof.

The figure of the accompanying drawing is an isometric view of the new design for mantels. Its leading feature is the design for a mantel comprising the columns supporting the mantel shelf.

Numeral 1 denotes the mantel shelf which has an inwardly curved front outline 2 and has its angular ends supported upon capital extensions 3. Beneath these and separated therefrom by an entablature are the approximately cylindrical columns 5 fluted at their lower ends and standing upon pedestals 6,

which also support the mantel posts or columns 7. 8 denotes engaged columns of rectangular form in cross section and fluted similarly to columns 5. They are situated to the rear and inwardly from the latter columns and contiguous to posts 7. All these columns have a similar and continuous entablature 9.

Surmounting the shelf 1 is a frame 10 having at each end a vertical row of rectangular panels. Between these adjacent to the panel opening 11 are two columns 12 which support an overhanging entablature 13 the cornice 14 of which is continuous with that of the frame. 35

What I claim is—

The design for a mantel as shown and described.

In testimony whereof I affix my signature in presence of two witnesses.

JOHN F. A. HOORT.
